UNITED STATES PATENT OFFICE.

ROBERT FREW, OF PITTSBURG, PENNSYLVANIA.

SEAL-LOCK.

SPECIFICATION forming part of Letters Patent No. 274,929, dated April 3, 1883.

Application filed September 27, 1882. (Model.)

To all whom it may concern:

Be it known that I, ROBERT FREW, of Pittsburgh, in the county of Allegheny and State of Pennsylvania, have invented a new and useful

5 Improvement in Seal-Locks for Railroad-Cars; and I do hereby declare the following to be a full, clear, and exact description thereof.

My improvement relates to an improvement in that class of seal-locks wherein the 10 seal is composed of a frangible material and arranged in connection with the lock so that it can be released by the fracture of the seal. It is designed for use on freight-cars, and also on other articles where a seal-lock is required.

15 I will now describe my invention, so that others skilled in the art may manufacture and use the same, reference being had to the accompanying specification, in which—

Figure 1 is a side elevation of the lock as 20 applied to a freight-car. Fig. 2 is a cross-section of the same, and Fig. 3 is a rear elevation of the lock.

Like letters refer to like parts wherever they occur.

25 In the drawings, *a* represents the front plate of the lock, which is attached to the side of the car by bolts or screws. Extending through the plate *a* and the side of the car is a rod or shaft, *b*, having an arm or lug, *c*, keyed to its 30 end outside of the plate *a*. This shaft is secured on the inside of the car or the plate *a*, so as to prevent its being removed, and yet so as to allow of an axial movement. Keyed to the shaft *b*, behind the plate *a*, and fitting

35 in a recess in the side of the car, is a ratchet-wheel, *d*, which engages with a pawl, *e*, so as to permit of the shaft *b* being moved axially, but in one direction. A spring, *f*, bears on the pawl *e*, so as to cause it at all times to

40 engage with the ratchet-wheel *d*. On the face of the plate *a*, below the shaft *b*, is a bracket, *h*, for holding the seal *i*. This seal may be formed of any frangible material—such as glass or metal—and it is provided with a lug 45 or projection, *j*, forming an integral part of the same. Attached to the door of the car is a pivoted bar or hasp, *k*, provided with one or more slots, *l*, extending through the same, and adapted to allow of the passage through them

50 of the arm *c*, when the arm is in a horizontal position. This pivoted bar or hasp *k*, when in position for locking, crosses the top of the seal-bracket *i*, so that the seal cannot be withdrawn without removing the hasp. By such

an arrangement of the parts I am enabled to 55 use an imperforate seal, which is much more readily and cheaply made and applied than one which has to be perforate, so as to pass over the key or rotating shaft.

The operation is as follows: The door of the 60 car having been closed, the arm *c* is brought into a horizontal position, extending from the shaft toward the door of the car. The seal *i* is then placed in the bracket *h*, and the hasp *k* is brought into position, so that the arm *c* 65 shall pass through the slot *l*. The shaft *b* is then turned on its axis until the arm *c* engages with the projection *j* on the seal *i*, which prevents the shaft being turned farther in this direction, while the pawl and ratchet-wheel *d* prevent the movement of the shaft in the reverse direction. The seal is thereby secured in the bracket, and the door of the car is securely locked, and cannot be unlocked without breaking the seal, so as to remove the 75 projection *j* and allow the arm *c* to be again brought into a horizontal position, extending toward the door of the car, when the hasp *k* may be released from the arm *c* and the door 80 opened.

The advantages of my invention are that it is simple, cheap, and easily operated, and affords a perfect protection to the lock, and obviates the necessity of using a chain and pin. The shaft *b*, being keyed inside of the 85 car, the lock cannot be removed from the outside by removing the bolts or screws which secure the face-plate *a*.

Having thus described my invention, what I claim, and desire to secure by Letters Patent, is—

In a seal-lock, the combination of a locking lug or key mounted on a shaft adapted to rotate in a single direction, a seal-retaining bracket arranged in the path of the rotating 95 locking-lug, and a slotted hasp adapted to encircle the locking lug or key, and arranged to cross the mouth of the seal-bracket to secure the seal therein, substantially as and for the purpose specified.

In testimony whereof I have hereunto set my hand this 20th day of September, A. D. 1882.

ROBERT FREW.
